UNITED STATES PATENT OFFICE

170,073

ROCKER CHAIR

Romeo A. Beaudette, Mankato, Minn.

Application October 29, 1951, Serial No. 17,164

Term of patent 14 years

(Cl. D15—6)

To all whom it may concern:

Be it known that I, Romeo A. Beaudette, a citizen of the United States of America, residing at Mankato, Minnesota, Blue Earth County, have invented a new, original, and ornamental Design for Rocker Chair, of which the following is a specification, reference being had to the accompanying drawing, forming a part hereof.

Fig. 1 is a front elevation of a rocker chair embodying my new design;

Fig. 2 is a side elevation of the same;

Fig. 3 is a rear elevation of the same; and

Fig. 4 is a top plan view of the same.

I claim:

The ornamental design for a rocker chair, substantially as shown.

ROMEO A. BEAUDETTE.
